UNITED STATES PATENT OFFICE

1,936,705

AUTOMATIC RAILWAY BLOCK SIGNALING
SYSTEMHarry D. Abernethy, Cleveland, Ohio, assignor
to The Union Switch & Signal Company,
Swissvale, Pa., a corporation of Pennsylvania

Application April 19, 1927. Serial No. 184,884

8 Claims. (Cl. 246—34)

This invention relates to a novel and improved automatic railway block signaling system intended to dispense with all movable parts usually employed in connection with such systems.

5 The prime object of this invention is to provide novel means constituting electrical controlling circuits whereby railway block signals are successfully and practically operated without the use of relays, movable contacts, or other movable parts by direct and alternating currents.

Another object of the invention is to so construct this signaling system that the controlling electrical circuits will successfully operate suitable or desirable railway block signals by a combination of alternating and direct or unidirectional current, and at the same time dispensing with all movable parts in connection therewith.

In the present art of railway block signaling systems usually employed, use is made of relays, 20 so-called, which are equipped with coils for receiving electrical energy from one source and controlling electrical energy from another source by moving one or more contacts from one position of engagement to another by means of the magnetic influence set up in the coils. These relays have to be carefully constructed and frequent tests made of them to insure that the physical movement of the armature and contacts are free and that the contacts have proper adjustment, clearance, etc., while my invention is so devised as to dispense with all movement of parts and obtain the same signal operation as is attained by relays with their movable armatures and contacts.

35 The foregoing and such other objects as may appear from the ensuing description are accomplished by the construction, arrangement, location and combination of the several parts hereinafter more fully described, illustrated by the accompanying drawing, and particularly pointed out in the claims appended hereto, it being understood that slight changes in the precise proportions and minor details of construction may be resorted to without departing from the spirit 40 or sacrificing any of the advantages of the invention.

In the accompanying drawing forming a part of this specification it will be seen that.

Figure 1 is a diagrammatic view showing means 50 embodying the basis of this invention, and

Figure 2 is a diagrammatic view showing the invention as applied in connection with automatic railway block signaling.

In the embodiment of my invention as illustrated in Fig. 1, the letter A designates an iron

frame, preferably constructed of thin strips of iron, or laminations with openings B formed therethrough for the winding of wire on the portions C, D and E; the windings to be formed of a suitable number of turns, such as may be required for the particular work to be done. The winding on portion D is connected to some desirable source of power, as represented at F which may be a continuous or pulsating electrical current, and controlled by some suitable means such as a switch G and in this case is the controlling circuit, although the windings C and E may be used as the controlling circuit.

The windings on portions C and E are also connected to some source of energy such as H which must be an alternating current, and are so connected together that the direction of magnetic flux set up in the iron frame A by current from alternator H through the windings is the same, and therefore the current is limited to a very small value of self-induction, exactly as in a transformer. These lines of force or magnetic flux are represented by the arrows shown in Fig. 1. The windings on portion C and E are of the same number of turns.

When switch G is closed direct or unidirectional current from the source F flows through the winding on portion D and the magnetic flux, or lines of force, set up by this current in the winding has the effect of increasing flux in the iron frame to such value that the limiting effect of self-induction in coils C and E is destroyed, that is, the iron in the frame is approaching magnetic saturation. The current is permitted to greatly increase from alternator H through coils C and E and through incandescent lamp I thereby causing the filament to glow. The lamp I may designate any piece of apparatus which it is desired to control.

By this method of connecting coils C and E together no electro-motive force is induced in coil D, and if wire J and K are connected together, as shown by the dotted line in Fig. 1, no change will occur in the circuit through coils C and E.

The functions of the coils D, C and E may be reversed, that is, C and E may be used as the controlling coils and D the controlled circuit. Also more than one circuit may be controlled by using separate coil or coils for each circuit.

Now by reference to Fig. 2 of the drawing, the following will describe how the means shown in Fig. 1 is adapted to control automatic signals for railways.

The letters R and R' represent the rails of a

- railway bonded together at their ends and insulated at each signal, as shown at U, U', U''. Current is supplied to the rails at the outgoing end of a block section and is furnished through wires 5 10, 11, 12 and resistance 13, which resistance is used to adjust current to the rails from some source of direct, unidirectional or pulsating current, not shown. The entrance end of the block section is connected by means of the wires 14 10 and 15 to coil D which functions as heretofore referred to in connection with Fig. 1, coils C', D and E' being part of the apparatus as explained.

With a train in the block as at M this track current referred to in the preceding paragraph 15 will be shunted out of the coil D and permit the current from secondary coil 16 of transformer 3 to flow through wire 17, and resistance 18, and wire 19, through the filament of red lamp 1' causing filament to glow and produce a red light 20 or signal warning following trains of presence in the block of a train at M, through wire 20 returning to secondary coil 16. The circuit of the red lamp 1' is a simple circuit starting from secondary of transformer 3, whose primary 5 is energized from power lines 6 and 7 through wires 25 8 and 9. Starting at coil 16 circuit is through wire 17, resistance 18, wire 19, filament of lamp 1', wire 20 back to secondary coil of transformer. This circuit includes part of secondary coil of 30 transformer 3 and a certain current flows due to voltage impressed on secondary coil by primary coil 5. No current can flow through wire 21 coil E' and C' because coil D is not energized by current from track through wires 14 and 15 35 due to wheels and axles of train shunting current from this coil.

When the train passes from M to the next block, as shown at N, current will flow from secondary coil 16, through wire 17, portion of resistance 40 18, wire 21, through coil E', coil C', wire 23, wire 25, filament of yellow lamp 2', wire 26, secondary coil 27, to secondary 16.

The flow of current from the source of power at the outgoing end of the block through rails and 45 coil D at the incoming end of block permits the passage of the above-described current. This flow of current through portion of resistance 18 causes reduction in current and voltage applied to the circuit for the red lamp of sufficient amount 50 to allow the filament of the red lamp to cool off and show no light.

The current flow through the yellow lamp filament hereinbefore described is of sufficient value, due to increased voltage added to the circuit by 55 the secondary coil 27, to cause the filament to glow and display a yellow light to approaching trains. This yellow light indicates to trains that the immediate block ahead is clear.

The same effect and circuits herein described in 60 connection with the operation of signal at U is present at signal at U' and U'', and as many succeeding block sections as may be desired and constitute my improved automatic block system.

At T is shown a circuit which can be used to 65 control any additional signal indication which may be desired, or can be used to control any other apparatus, such as an alternating current relay.

This particular circuit system comprises only 70 one of many various combinations which may be employed in connection with the different electrical methods of signaling and is intended to demonstrate the use of the system disclosed in Fig. 1 of the drawing.

In addition there are many other possible uses 75 to be made of this controlling apparatus, such as

controlling current for motors, etc. at remote points, and it will be readily obvious that the signals do not have to be necessarily of the electric light type, but may be of the motor type.

It will be understood that the device such as 80 illustrated in Fig. 1, which shows a type of transformer construction, is not used as a transformer, but is employed as what may be properly termed a current choking apparatus.

Having thus described my invention what I 85 claim and desire to secure by Letters Patent is:

1. A railway signaling system of the character described, comprising means by which a direct or unidirectional electrical current in the track rails controls a signal operating current by means of an 90 electro-magnetic translating device, all parts of said system being stationary.

2. An automatic block signaling system for railways, comprising alternating current means for displaying signal indications, resistances used in 95 connection with said indications for dividing the current, direct or unidirectional current means for controlling the alternating electrical current means to display proper signal indication, all of the parts of said system being stationary. 100

3. An automatic block signaling system for railways, comprising means formed of stationary iron cores and coils to control alternating current signal indications, means for choking the alternating electrical current in connection with said signal 105 indications, and means whereby a direct or unidirectional current controls said choking of said alternating electrical current for operating a signal.

4. In combination, a section of railway track, 110 a source of current connected with the rails of said section, a device having a magnetizable core provided with a winding controlled by current received from the rails of said section and in turn acting to vary the permeability of at least 115 a portion of said core, an output circuit including a source of alternating current and a winding of said device for varying the amount of current flowing in said circuit in accordance with variations of the permeability of said core caused 120 by said control winding, and a signal for said section controlled by said output circuit.

5. In combination, a section of railway track, 125 a source of current connected with the rails of said section, a device having a magnetizable core provided with a winding controlled by current received from the rails of said section and in turn acting to vary the permeability of at least 130 a portion of said core, a signal for said section, and a control circuit for said signal including a source of alternating current and having its impedance varied in response to variations of the permeability of said core.

6. In combination, a section of railway track, 135 a source of current connected with the rails of said section, a device having a magnetizable core provided with a winding controlled by current received from the rails of said section and in turn acting to vary the permeability of at least 140 a portion of said core, a signal for said section, and a control circuit for said signal including a source of alternating current and a winding of 145 said device the impedance of which is varied in response to variations of the permeability of said core.

7. In combination, a section of railway track, 145 a source of current connected across the rails of said section, a device located in the trackway and having a magnetizable core provided with a winding which is connected across the rails of 150

said section and which serves to vary the permeability of at least a portion of said core in accordance with variations of the current flowing in the track rails, a signal located in the trackway for governing traffic through said track section, and a circuit including a winding linking said core and controlling the signal in response to variations in the permeability of said core.

8. In combination, a section of railway track, 10 a source of current connected across the rails of said section, a device located in the trackway

and having a magnetizable core provided with a winding which is connected across the rails of said section and which serves to vary the permeability of at least a portion of said core in response to variations in the current received from the track rails, a signal located in the trackway and governing traffic through said section, and a control circuit for said signal responsive to variations in the permeability of said core caused by variations in the current flowing in said winding. 85
